AUTOMATIC ELECTRIC CHANGE-OVER FOR
MOVING PICTURE MACHINE SHUTTERS

Cecil E. Hall, Freeport, Tex., assignor of five per cent to D. W. Scott, Jr., Freeport, Tex., and seven per cent to Geo. D. Reeves, Brazoria County, Tex., and eighty-eight per cent to Gladys Lehde

Application February 20, 1931, Serial No. 517,234
Renewed September 30, 1935

4 Claims. (Cl. 88—16.2)

The invention relates to an improvement in mechanism for operating the shutters to close off the showing of the film on the screen in connection with moving picture machines.

With the advent of talking pictures it is essential that the change-over of one machine to the other be complete, instantaneous, and at the exact instant when the film reaches the desired position and when the sound apparatus is also in the proper position. As is now the practice it is necessary for the operator, in some installations, to manipulate one control to change over the machine, one control to change over the sound apparatus, and one control to change over the shutters which govern the exposure of the film to the screen. In some installations the change-over of the film and the sound mechanism is accomplished simultaneously so that it is necessary for the operator to perform two or three distinct operations almost simultaneously in order to effect a perfect change-over. The arrangement of the machines and controls in many installations make such a change-over practically impossible and necessitates the presence of at least two operators in order to effect a complete change-over in the proper manner.

It is one of the objects of this invention to provide a mechanism in combination with the sound and machine change-over which will enable the operator to perform the change-over by a single movement of one control and particularly so that the shutters on the front wall of the booth will be changed over at the same time that the change-over in the sound mechanism is accomplished.

Another object of the invention is to couple a mechanism with the sound change-over so that the shutters on the booth will be changed-over automatically.

Another object of the invention is to provide a pair of shutters wired into a circuit which is controlled by a manipulation of the moving picture machine change-over.

A still further object of the invention is to provide a mechanism which will operate automatically to open one shutter and close the opposite shutter in accordance with the machine which is to be placed in operation.

Other and further objects of the invention will be readily apparent when the following description is considered in connection with the accompanying drawing wherein:

Fig. 1 is an elevation of the front wall of a moving picture machine booth which has been equipped with the invention.

Fig. 2 is an elevation taken at right angles to Fig. 1 and showing the automatic change-over switch.

Fig. 3 is a section taken on the section line of Fig. 2, and looking in the direction of the arrow.

The invention will be understood by having reference to Fig. 1 wherein the front wall of the booth is indicated at 2. Mounted on this wall as a part of the standard installation of talking picture machines is a control apparatus indicated at 3 and designated as a fader. This fader is of standard construction and does not constitute a part of this invention, but includes a mechanism for changing both the film and the sound mechanism from one machine to another in order that a continuous showing of the film on the screen may be accomplished. 4 indicates a lever which may be used to cut out either the film or the disc when it is desired to change-over either one, independently of the other, so that any desired sound may be used with any picture.

Control of the fader is accomplished by means of a dial 5 which is carried by a bearing 6, and is connected with a shaft 7. Numerals 8 are provided on the dial 5 so that the operator may know the amount of sound which is to be used in connection with the particular film or sound mechanism then in use. The digit 0 indicated at 9 is the zero, or change-over point so that when the dial 5 is rotated so that this digit 0 passes the arrow 10 one machine will be thrown into operation and the other machine will be discontinued. This fader derives its name due to the fact that it fades the sound from one disc or record into the next disc or record, so that the change-over is not perceptible to the audience and this change-over occurs when the dial 5 is rotated so that the zero 0 passes the arrow 10. It is usual to place the fader 3 as indicated on the front wall 2 of the booth and directly between the two moving picture machines which have not been shown. This position is inconvenient for the operator to manipulate the machine and for this reason the shaft 7 is extended at 11 and has mounted thereon what is known as the dummy fader 5'. This dummy fader is identical with the dial 5 but is in a convenient position for the operator to manipulate the same.

In changing over from one machine to another it is necessary that the exposure of the film on the screen be cut off from the machine which is to be discontinued and which has exhausted its roll of film, and the machine which is being placed in operation must be so oper-

ated that its film will be exposed simultaneously with the cutting off of the other film. It is usual to have openings such as 15 and 16 in the front wall of the booth, and it is through these openings that the light rays pass to the screen in the front of the theatre. Shutters 17 and 18 serve to close the openings 15 and 16, respectively, and it is the operation of these shutters and the control thereof as a function of the fader which is involved in this invention. The shutters 17 and 18 are identical, and for purposes of illustration the mounting of the shutter 17 will be described. This shutter is carried by a rod 20 which is disposed in a horizontal position and may in itself serve as a core for the solenoids 21 and 22, or the core of the solenoids may be connected to the rod 20. In either event, it is intended that when either of the solenoids are energized the rod 20 will be moved and carry with it the shutter 17. In the position as shown in Fig. 1 when the solenoid 21 is energized the rod 20 will be moved to the left, so that the shutter 17 will move over and cover the opening 15 to close off the exposure of film from the machine which is showing through this opening 15, whereas the solenoid 22 serves to move the shutter to open position so that exposure may occur through the opening 15. Stop members 23 are provided adjacent the end of the solenoids so that the rod 20 or the core of the solenoids will not move beyond a predetermined position.

The solenoids 21 and 22 are wired into an electric circuit indicated at 25 which may preferably be the usual 110 volt alternating current supply line available from a central source of power. This line as usual contains the positive wire 26 and the negative wire 27. The negative wire 27 is grounded to the wires 28 and 29 which are in turn connected with the solenoids 21 and 22. The positive wire 26 is connected with the switch 30 which controls the operation of the solenoids 21 and 22.

The grounding of the wires eliminates the possibility of a spark occurring when the mechanism operates and insures safety of the attachment. While two sets of solenoids have been shown it is intended that the rod 20 may be extended to carry both shutters and thus one solenoid 21 and one solenoid 22 may be dispensed with.

The switch 30 is best seen in elevation in Fig. 2 and includes the center blade or finger 31 and the contacts 32 and 33. The finger 31 is mounted on a pivot at 34 so that it may oscillate to come into engagement with either of the contacts 32 or 33. A flat spring 35 is shown as positioned so that the finger 31 will normally be retained in a vertical position by frictional engagement with this spring. In this manner any tendency to vibration on the part of the finger will be eliminated and its swinging movement will be damped so that a single impulse will be transmitted to the solenoids when the finger 31 is moved and it will be impossible for the finger 31 to swing on the opposite side of the center and make an engagement with the other contact. The finger 31 is shown as having a wire 26 connected thereto through the pivot 34. The contacts 32 and 33 are connected with wires 37 and 38, respectively, which extend to the windings of the solenoids 21 and 22.

In order that operation of the finger 31 may be accomplished simultaneously with the movement of the fader dial, a cam 40 has been fixed to the shaft 11 in a proper radial position, so that it will engage with the head 41 on the finger 31. The cam 40 is beveled on each side at 42 so that it will gradually move the finger 31 away from its vertical position and into position of one of the contacts 32 or 33 depending upon the direction of rotation of the fader. The cam 40 is so positioned that the circuit to the solenoids will be closed by engagement with the finger 31 and the proper contact at the same time that the zero 0 on the fader dial passes the arrow 10. The closing of the circuit to the solenoids 15 will energize that solenoid which will exert a pull on the rod 20 and move the shutters in the direction desired. As seen in Fig. 1 the shutter 17 is in open position and the shutter 18 is in closed position, so that in each instance the solenoid on 20 the left hand side will be energized to accomplish the desired movement of the shutter, and the wiring has been illustrated as arranged to accomplish this result.

While a certain form has been shown of the switch 30 it is intended that this switch may take any desired form as it is broadly the intention to couple up the operation of the shutters with the operation of the fader so that the operator may accomplish the change-over of the 30 shutters at the same time that he accomplishes change-over of the machine and the sound mechanism.

Having described my invention, what I claim is:

1. In combination, a plurality of sound moving picture machines, a manually operated fader therefor, shutters for said machines, means including an electric circuit and a switch therein to operate said shutters as a function of the operation of said fader, and additional means operable by said fader to actuate said switch to cause movement of said shutters.

2. In a sound moving picture change over control system, a manually operated fader, an electric switch, cam means attached to said fader for moving said switch when said fader is moved to change over, and additional means including electrically operated projection shutters controlled by said switch.

3. In a sound moving picture change-over control system, a fader, an electric switch, a cam means attached to said fader, a finger on said switch for moving said switch when said fader cam is moved, and additional means including electrically operated projection shutters controlled by said switch, whereby the change-over and shutter operation will occur simultaneously and upon operation of the fader.

4. In combination, a pair of sound moving picture machines and a change-over control system, said system including shutters for said machines, a sound fader associated with said machines, means to actuate said fader comprising an elongated shaft having graduated dials spaced 65 therealong, an electric switch operable by said shaft and adapted to control an electric circuit to open and close the respective shutters whereby the machines and sound records are changed over simultaneously.

CECIL E. HALL.
